UNITED STATES PATENT OFFICE.

WILLIAM R. KINNEAR, OF COLUMBUS, OHIO.

RAILROAD-TIE.

SPECIFICATION forming part of Letters Patent No. 495,045, dated April 11, 1893.

Application filed September 2, 1892. Serial No. 444,871. (No model.)

To all whom it may concern:

Be it known that I, WILLIAM R. KINNEAR, a citizen of the United States, residing at Columbus, in the county of Franklin, State of Ohio, have invented certain new and useful Improvements in Railroad-Ties; and I do hereby declare the following to be a full, clear, and exact description of the same, together with the drawings forming part of this specification.

This invention relates to improvements in rail road ties and consists in the novel construction and arrangement of the parts as hereinafter set forth and described, and has for its objects to provide a metallic tie which will be inexpensive and durable, while providing a fastening easy of adjustment upon the rail and tie.

In the drawings: Figure 1 is a side elevation of this tie showing one side of the saddle. Fig. 2 is a side elevation of the same from the reverse side. Fig. 3 is a plan view of the tie and fastenings in position. Fig. 4 is a detail view of the side of the tie with fasteners removed. Fig. 5 is detail view of side of fastenings. Fig. 6 is a front view of same. Fig. 7 is side view of tie, and fastenings as arranged for the first step of setting the tie to rail already in position. Fig. 8 is a side elevation of an old rail showing the adaptation to this form of tie.

In former metal ties a difficulty has existed in that the substitution of the wooden tie by one of metal has necessitated the raising of the entire rail. It is designed by this invention to overcome this difficulty and permit of the substitution without affecting the other ties.

The letter A designates the tie, which may be constructed either of cast or rolled metal and is provided along the sides with the braces A³ to support the perpendicular flange A'. The perpendicular flange A' is provided at either end with the raised portion A⁴ which is cut away to form the knuckles A² and the recess between them. The base flange A is made of any desired width according to the strain.

Mounted on the perpendicular flange A are the fastenings B. These are provided with the clamping jaws B³ which are adapted to rest against the web of the rail under the tread. These fastenings are cut away at B⁴ to encom-

pass the flange of the rail and to form a seat for the rail near their junction. These cuts B⁴ are so shaped as to allow the rail to be raised by swinging the fastenings on the knuckles A² as shown in Fig. 7 of drawings. Fitting over the knuckles A² are recesses B⁵ formed in the fasteners B. By means of this construction any weight thrown on the rail, when in position within the fasteners as above described, operates to depress the lower part of the fasteners and to throw the clamping jaws B³ toward each other and against the interposed web of the rail, holding it the more rigidly in proportion as weight is added to the rail.

The lower part of the fasteners is divided to form the guide flanges B' and B² which fit snugly against the sides of the perpendicular flange A' and prevent any wobbling on the part of the fasteners, and further answer to maintain them in position on the tie.

The guide flange B' has a further function in forming an additional bearing to relieve the strain on the knuckles A². This is accomplished by extending the flange down to the base flange A of the tie and rounding it to a curve struck with the center of the knuckle for a center. By means of this construction I provide disadjustment which might occur by reason of the wear between the recess B⁵ and knuckle A² by throwing part of the strain upon this guide flange and base flange of the tie.

The guide flange B² is cut away as shown in drawings to permit of the fastenings being placed in position by slightly separating the tie and rail as shown in Fig. 7 of drawings, the maximum separation between the tie and rail required being not more than an inch.

In the alternative form of tie shown at Fig. 8 of drawings I have used old or dilapidated rails. By this means I save to the rail road the cost of additional metal and utilize the waste. To do this only necessitates cutting the tread of the rail away to permit the guide flanges B', B², to set down over the web; and forming the knuckle A² for the recess B⁵ of the fasteners, as shown, the dotted lines representing the fasteners in outline.

Having thus described this invention, what I claim is—

1. In a rail-road tie such as described, the

combination with knuckles integral with the tie, of fasteners having bearings on the said knuckles clamping jaws attached to the said fasteners and adapted to grasp the side of the rail, guide flanges adapted to straddle the said tie, and an extension from the said fasteners adapted to rest upon the tie and carry part of the weight, substantially as described.

10 2. In a rail-road tie such as described, the combination with the knuckles A² of fasteners

having bearings B⁵ on the said knuckles and forming supports for the rail between the said bearings, clamping jaws B³, and guide flanges B' and B² substantially as described. 15

In witness whereof I have hereunto set my hand this 18th day of June, 1892.

WILLIAM R. KINNEAR.
